UNITED STATES PATENT OFFICE.

BLOOMFIELD H. HOWARD, OF ASPINWALL, AND ERNEST J. TURNER, OF PITTSBURGH,
PENNSYLVANIA.

INGOT-MOLD AND FEEDER.

1,182,374.

Specification of Letters Patent.

Patented May 9, 1916.

Application filed September 11, 1915. Serial No. 50,166.

To all whom it may concern:

Be it known that BLOOMFIELD H. HOWARD and ERNEST J. TURNER, citizens of the United States, residing at Aspinwall and Pittsburgh, respectively, in the county of Allegheny and State of Pennsylvania, have invented certain new and useful Improvements in Ingot-Molds and Feeders, of which the following is a specification.

10 Our invention relates to molds and feeders for the manufacture of iron or steel ingots and has for its object to prevent or reduce to a minimum the formation of cavities, holes or seams, known as "piping" in 15 the upper portion of the ingot.

A further object of the invention is to produce an ingot mold entirely plain in structure, one that can be manufactured nearly as cheaply as an ordinary standard 20 ingot mold and at the same time produce better results than can be obtained by many of the expensive and complicated ingot molds that have been invented from time to time. Also to produce an ingot mold that 25 will possess sufficient strength so that it may be used in casting a very large number of ingots. In our experiments 138 ingots had been cast in a single mold which was still as strong apparently as in the beginning. 30 Further to provide said ingot mold with a practical feeder, one that can be manufactured cheaply and applied easily.

In short the general object of our invention is to produce a mold that can be manufactured cheaply, that will be practical and durable, that will be provided with a simple and inexpensive feeder of such construction that it can be applied to the mold quickly, all of which can be adopted in the 40 steel industry of today, without materially changing the systems in use and at the same time be the means of removing practically all piping from the product.

In our invention we prefer to use an ingot mold with comparatively thin walls at the top and increasing in thickness in a uniform line to near the bottom. By this means the heat is radiated from the ingot progressively being greatest and most rapid 50 at the bottom of the mold and decreasing uniformly toward the top of the mold there being no "thin parts" or "projections" to interfere.

With our invention ingots can be pro-

duced homogeneous throughout, and practically free from segregation and "piping".

The mold is made of steel and the feeder of any suitable refractory material.

A practical embodiment of our invention is represented in the accompanying drawings forming a part of this specification and in which like letters are employed to designate like parts throughout the several views.

In the drawing: Figure 1 is a vertical section of the preferred form of the ingot mold and feeder. Fig. 2 is a vertical section of the ingot mold with a modified form of feeder. Fig. 3 is a top view plan of ingot mold and feeder showing recesses for containing zigzag irons. Fig. 4 is a top view plan in which a straight feeder is used. Fig. 5 is a vertical section of the upper part of the ingot mold with feeder made so as to close space about feeder as shown by top view in Fig. 6. Fig. 6 is a top plan view of the feeder shown in Fig. 5. Fig. 7 shows the zigzag iron used to support the feeder in proper position and Fig. 8 is a perspective view of the zigzag iron made adjustable. Fig. 9 is a vertical sectional view showing the walls F and F' of the bore parallel.

Referring to the drawings, A is the ingot mold with walls B relatively thin at the top and increasing in thickness to a point C near the bottom. From the point C the wall B may continue to increase in thickness all the way to the bottom but we prefer not to have the wall B increase in thickness beyond the point C so that the ingot mold A will rest securely in the stool D. By this construction there are no weak places anywhere in the mold and the radiation of heat will uniformly decrease from the bottom to near the top. The cavity or bore E may be made with the walls F F' parallel, as shown in Fig. 9, or the diameter of the bore may increase from top to bottom or from bottom to top. In form, the mold A and its bore E we prefer to be made square with rounded corners. The mold A is fitted with any suitable lugs or ears G to which tongs, chains or other suitable means may be attached and the mold moved about or stripped from the ingot. If preferred ears H may be provided.

The feeder K is made substantially of the same shape as the cross section of the

bore E. In Fig. 1 it is shown with straight walls and supported by zigzag irons which may be made solid as shown in Fig. 7 and of comparatively thin iron so that the space 5 between the feeder K and the walls F F' may be as small as possible, or adjustable zigzag irons M' may be made as shown in Fig. 8 so that the depth to which the feeder K is suspended may be regulated. The 10 hanger M' is made in two parts with the end of one member bending outwardly, the other inwardly, and held together by bolts passing through slots in both members.

In Fig. 3, a feeder K' is shown with recesses N, into which zigzag irons M fit snugly so that the space between the feeder K' and the walls F F' of the bore E will be reduced to a minimum.

In Figs. 5 and 6, K² is a modified form 20 of feeder with a collar O, extending around the lower portion and containing recesses N' through which the zigzag irons, M, may pass.

In Fig. 2 is shown a modified form of 25 feeder K³ in which the upper portion is made to flare outwardly and rest upon the top of the wall B at P.

The practical working of our invention is as follows: The ingot mold A is placed 30 on the stool D, the zigzag irons M, are put in position and the feeder K placed within the mold resting on the lower end of the hanger. The cavity E is filled with molten metal. The heavy walls at the lower portion 35 of this ingot mold A rapidly radiate heat and freezing of the ingot begins at once. As the molten metal rises to higher levels the radiation is less rapid until the feeder K is filled, the refractory material 40 of which conserves a considerable amount of heat and keeps the upper portion of the ingot in a molten state until the cavities formed by the contraction of the metal are filled producing a solid ingot practically 45 free from piping and segregation, with but a small portion of the upper end to be scrapped. When the ingot is sufficiently solid to handle, chains or tongs fastened to a crane are attached to the lugs G and 50 the ingot mold A is stripped off the ingot. There is always a very considerable amount of friction between the ingot and the mold and it requires much force to separate them. For this reason our ingot mold is designed

with no weak places or thin walls that invariably break when subjected to the rough usage necessary in the steel practice. 55

Having thus described our invention what we desire to secure in Letters Patent is:—

1. A mold having its walls relatively 60 thin at the top and increasing in thickness toward its lower end, a feeder fitting in the mold, and an adjustable hanger for the feeder in the mold and supported by the upper end thereof, said feeder having 65 grooves through which the hanger passes whereby the feeder will snugly fit the cavity of the mold.

2. A feeder for ingot molds adapted to 70 fit the cavity of the mold and having means to allow a hanger to pass into the mold and support the feeder from its lower end.

3. The combination with an ingot mold, 75 of a feeder adapted to fit the cavity of the mold and a hanger engaging the upper end of the mold and the extreme lower end of the feeder.

4. The combination with an ingot mold, 80 of a feeder adapted to fit the cavity of the mold, and an adjustable hanger engaging the upper end of the mold and the lower end of the feeder.

5. The combination with an ingot mold, 85 of a feeder adapted to fit the cavity of the mold and having passages therein, and a hanger engaging the upper end of the mold and passing through the passages and engaging the lower end of the feeder and supporting the same.

6. A feeder for ingot molds adapted to 90 fit the cavity of the mold and having passages to allow hangers to pass to the lower end thereof for supporting the same within the mold.

7. The combination with an ingot mold, 95 of a feeder adapted to fit the cavity of the mold and having passages therein, and hangers within the passages having outwardly turned upper ends engaging the top of the mold and inwardly turned lower ends 100 engaging the bottom of the feeder.

In testimony whereof we affix our signatures in presence of two witnesses.

BLOOMFIELD H. HOWARD.

ERNEST J. TURNER.
